UNITED STATES PATENT OFFICE.

HENRY PRICE BALL, OF BROOKLYN, NEW YORK, ASSIGNOR TO S. STERNAU & CO., INC., OF BROOKLYN, NEW YORK, A CORPORATION OF NEW YORK.

STOVE FOR BURNING SOLID FUEL AND PROCESS OF MAKING SAME.

1,268,786.

Specification of Letters Patent.

Patented June 4, 1918.

Application filed November 17, 1916. Serial No. 131,855.

To all whom it may concern:

Be it known that I, HENRY PRICE BALL, a citizen of the United States, residing in Brooklyn, county of Kings, and State of New York, have invented a certain new and useful Stove for Burning Solid Fuel and Process of Making Same, of which the following is a specification.

This invention relates to improvements in stoves or lamps, which burn a solid fuel composed of alcohol and an absorbent and has for its objects—

- 1st. To improve the appearance of the container when it is open.
- 15 2nd. To observe leaks in the container so that defective stoves may be discarded.
- 3rd. To automatically repair small and trivial leaks without appreciable loss of fuel.
- 20 4th. To produce printed matters, in relief or intaglio, on the top of the fuel to be exposed to view when the cover is removed.

These and further objects will more fully appear in the following specification and accompanying drawings, considered together or separately:

In the drawings—

Figure 1 is a section of a container, with the cover removed, showing it in the first stage of the process.

Fig. 2 is a similar view, but with the cover in its first position.

Fig. 3 is a similar view, with the cover in its final position.

Fig. 4 is a similar view, showing the next step in the process in which the container is reversed.

Fig. 5 is a similar view, of the completed stove but with the cover removed.

Fig. 6 is an enlarged section of a portion of the upper part of the stove showing it in reversed position and indicating the manner in which leaks are automatically repaired and.

Fig. 7 is a detail sectional view showing a modification of the manner in which the air space may be formed.

In all of the several views like parts are designated by the same reference characters.

In carrying out my invention I provide a container 1. This container is made of sheet metal or other material which will suitably resist the action of heat. It is adapted to serve as a means for transporting and storing solid fuel and also as a stove for burning said fuel. The container is provided

with a suitable top 2, of any size. Associated with this top is a cylindrical neck 3. In the embodiment chosen for illustration, this neck extends inward. That portion 4 of the container opposite the neck may be bulged inwardly. The bulge may, if desired, be dispensed with and the bottom of the container made of any other shape. In Fig. 7 it is shown as flat.

Associated with the container is a cylindrical cover 5 having a peripheral flange 6 thereon. The cover is of such a size that it will make a close fit with the inside of the cylindrical neck 3. By means of this close fit it is held in place by friction and a liquid and vapor tight joint is produced between the side walls of the cover and the cylindrical neck. The peripheral flange serves as a convenient means for removing the cover by the introduction of a suitable tool under it. Preferably the cover is provided with an embossed design 7 in the form of words or figures or the like. Preferably this embossed design is made by distorting the sheet metal forming the cover so that the design may be in relief on the upper side of the cover and in intaglio on the under side.

Associated with the container hereinbefore described is a suitable fuel. This fuel is preferably made of alcohol and an absorbent. Preferably this absorbent is in the form of a soap. A suitable soap is made of stearic acid and sodium hydroxid. As an example, I may embody alcohol, one hundred parts, stearic acid, and sufficient sodium hydroxid to neutralize all or nearly all of the stearic acid. The fuel is compounded in the presence of heat and when hot is in the form of a liquid. This liquid, indicated at 8 in Figs. 2 and 3, is introduced within the container so that its top line 9 is below the top of the container. The cover is then introduced within the cylindrical neck and pushed down from the position shown in Fig. 2 to that shown in Fig. 3, or lower or higher as desired. The air or vapors within the container will be compressed but there will be sufficient space for them under the cover and in the annular space 10 below the top and alongside of the neck and cover, so that they may be compressed without putting undue strain upon the container and cover.

The container is then reversed to such an extent that the liquid will cover the bottom of the cover 5, the bottom of the top 2,

the seam between the top and the sides of the container and the joint between the cover and the neck 3, as shown in Figs. 4 and 7. The liquid fuel will then enter the now 5 lower part of the container and rest upon the lower face of the cover and also upon the lower face of the top 2. The air or vapor space 11 will then be adjacent to the bottom 4 of the container. Preferably the 10 bulge in the bottom 4, when employed is sufficiently deep so that the liquid fuel will, when the container is reversed, be in contact with some, preferably the central, part of it as shown in Fig. 4. The fuel is now 15 allowed to harden by cooling and during the cooling operation as the mass contracts the central portion will adhere to the bulge and the level of the edge of the mass will be lowered thus forming a more or less conical 20 shape, approximately as shown in broken lines in Fig. 4, so that when the container holding the hardened and solidified fuel 12 is reversed, as shown in Fig. 5, there will be an air or vapor space 11 adjacent to the 25 bulge and the solidified fuel will be supported on the bulge. At the same time the solid fuel will be in close and intimate contact with the lower side of the top 2 and cover 5. When the cover is removed, for the purpose 30 of exposing the fuel for burning, the embossed design 13 will appear either in relief or intaglio, on the top of the solid fuel and may be observed through the cylindrical neck.

15 As shown in Fig. 7 a container having a flat bottom is employed. When the cover is placed in position the container is partly inverted, the liquid will seek the lower level and the space 11 will be left at the highest 0 point in the container. When the fuel solidifies and the container is placed bottom down the fuel will be supported on the bottom of the container.

In the event that a leak occurs in one of 5 the joints, for example, between the neck and the cylindrical cover, or at the seam between the top and the sides of the container, the pressure of the air or vapor contained in the space 11 shown in Fig. 4 will force the liquid 0 fuel through such joint. This fuel will then be forced upon the support carrying the container and the operator or workman, who is filling the container, will observe that a leak has appeared and then can discard the 5 container. In the event that the leak is very small, for example, through the faulty seam 14, shown in Fig. 6, then there will be a very small escape of fuel. When the fuel hardens the alcohol will evaporate in the immediate 0 vicinity of the joint, leaving the solid absorbent 15 adjacent to such joint. This solid absorbent in the embodiment chosen for illustration, being a soap formed of stearic

acid and sodium hydroxid, will act as an effective dam to prevent further escape or 65 evaporation of the liquid alcohol. The amount which will have escaped previous to the formation of this dam will be very little and the container will therefore be as good in all practical respects as the one without 70 the leak.

I regard the feature whereby the upper part of the container is filled with solid fuel as very important. In addition to indicating the presence of leaks, or to automatically 75 repair small leaks, as hereinbefore described, and the imprinting of designs or other matter on the upper surface of the fuel through the agency of the cover, as also hereinbefore described, the container with the cover removed has a much more pleasing appearance than one which does not have the completely filled appearance of my improved stove. This is made possible through the air spaces 11, which permit the cover to be closed and 85 at the same time fill the entire upper part of the container.

Having thus described my invention what I now claim as new and desire to secure by Letters Patent, is:

90

1. As a new article of manufacture, a container having an open end, a cover coöperating with the opening, a solidified fuel filling the container in close contact with the cover, there being a space between the fuel and the 95 bottom of the container.

2. As a new article of manufacture, a stove comprising a sheet metal container, having a cylindrical neck, a cylindrical cover coöperating with said neck and movable 100 longitudinally therein, with a solid fuel composed of a mixture of alcohol and an absorbent, said fuel filling the container in close contact with the neck and cover, and resting on the bottom, with an open space between 105 the fuel and a portion of the bottom of the container.

3. The process of making stoves, which consists in partly filling a sheet metal container having a cylindrical neck, and a cylindrical cover coöperating with said neck and movable longitudinally therein, with a melted liquid fuel composed of a mixture of alcohol and an absorbent, introducing the cover into the neck to compress the air or 110 vapor in the space above the fluid, then reversing the container and allowing the contents to cool and solidify, leaving an open 115 space between the solidified fuel and the bottom of the container.

This specification signed and witnessed this fifteenth day of November, 1916.
